(57) **CLAIM**

The ornamental design for a IR headband with neck coverage, as shown and described.

DESCRIPTION

FIG. 1 is a perspective view of the IR headband with neck coverage showing my new, original, and ornamental design;

FIG. 2 is a front perspective view thereof;

FIG. 3 is a back perspective view thereof;

FIG. 4 is a left side view thereof;

FIG. 5 is a right side view thereof;

FIG. 6 is a front view thereof;

FIG. 7 is a back view thereof

FIG. 8 is a top view thereof; and,

FIG. 9 is a bottom view thereof.

The broken lines are for the purpose of showing environmental subject matter and form no part of the claimed design.

1 Claim, 5 Drawing Sheets
